AMUSEMENT GAME

Edward P. Stein, Fulton D. Thornton, and Robert Morris, Chicago, Ill., assignors of one-half to John A. Russell, Chicago, Ill.

Application December 28, 1934, Serial No. 759,538

7 Claims. (Cl. 273—121)

Our invention relates to improvements in an amusement game of the ball projecting type having a playing board inclined or sloped from the horizontal so that balls may gravitate down the same into holes formed through the board to trap the balls. These holes may have certain values to encourage skill and competition among several players. For instance, in the form of the game herein to be disclosed it is intended to simulate the well known card game of poker in which 5 give cards are drawn. Accordingly, the holes in the preferred embodiment of our game are given designations corresponding to those used in a deck of playing cards. When a projected ball is 10 trapped by a hole the ball moves down an under guide to set and hold in place a register having thereon a card value designation corresponding with that of the hole which received the ball. Obviously, in such game it is not desirable to trap more than one ball in each hole and therefore we provide each hole with a 15 normally open check or trap door hingedly mounted in the holes and having a trip leg portion formed therewith to receive the ball dropping through the hole to hinge or pivot the trap door or check to hole closing position.

Adjacent the lower end of the game board are two register slots or openings, spaced apart and constituting blank poker hands, the registers being located thereunder and normally in non-indicating position until moved and held by a trapped, guided ball to a card showing or indicating position. The game may employ ten balls, five of which are small and five of which are somewhat larger. The small balls are for setting cards, or registers in one blank hand and the five large balls are for setting the cards or registers in the other hand. By this arrangement two 20 players may compete in drawing five cards, so to speak, to build up a poker hand, each player having five balls of one size to play in accomplishing the purpose.

The game is designed to be coin released, all 25 ten balls being made available for play at one release operation, the ball routing means being such that the balls are segregated as to size. A lifter is used to elevate the balls one at a time for projection over the board from a ball segregating and accumulating trough. When the 30 game is released for play shiftable means effects resetting of all registers to non-indicating position to create blank hands and at the same time any closed trap doors are moved to hole opening position.

55 The primary object of our invention is to pro-

vide a ball closed trap door for the holes in the game board.

Another important object is to provide an improved ball moved and ball set register for designating in a simple, effective manner which hole 5 has trapped a ball.

Still another very important object is to provide a coin released shiftable or other movable means for resetting the trap doors to hole uncovering position and for returning the registers 10 to non-registering position. Of course, other equally important objects will become apparent as this description continues.

While the structure of our invention is herein described in connection with the playing of a 15 two handed simulated poker card game, it will plainly be apparent that this is only done in an illustrative sense, for obviously the structure may serve in many other forms, such for example, as merely giving to the holes number values and 20 applying corresponding numbers on the registers.

In the drawings showing a practicable form of the invention:

Figure 1 is a general plan view of the amusement game;

Figure 2 is another plan view of the under or ball guide structure as viewed from the line 2—2 of Figure 6, looking downwardly;

Figure 3 is an enlarged, transverse, fragmentary, sectional view through this ball routing guide structure taken along the line 3—3 of Figure 2;

Figure 4 is a longitudinal, enlarged, detail sectional view through a ball trap and hole as taken along the section line 4—4 of Figure 1;

Figure 5 is a front view of the structure shown in Figure 4 as viewed along the section line 5—5 in Figure 4, looking in the direction of the arrows;

Figure 6 is an enlarged side sectional view 40 through the game as taken along the center line 6—6 of Figure 1, looking in the direction of the arrows;

Figure 7 is an enlarged detail plan view of the under shiftable mechanism for resetting the trap 45 doors and registers, the view being taken along the line 7—7 of Figure 6, looking downwardly;

Figure 8 is an enlarged, detail, sectional, elevational view of the ball lifter and associated ball feeding trough taken along the line 8—8 of Figure 1, looking in the direction of the arrows;

Figure 9 is a detail cross sectional view through the guide between the top board and guide or alley panel as seen along the line 9—9 of Figure 4 to show its cross section;

Figure 10 is a similar view of the same guide taken along the line 10—10 of Figure 4;

Figure 11 is an enlarged detail side elevational view, partly in section, to show a modified form 5 of register; and,

Figure 12 is a detail view, in perspective, of one of these modified, pivoted registers in segment form.

As shown in Figures 1 and 6 the game is housed 10 in a box 15 having a front wall 16, the box, or cabinet being closed at its top by a glass panel 17. The game board is shown at 18 the same being sloped from the horizontal with its low end toward the front wall 16. At the right hand side 15 of the board 18 is a ball projection passage 19 and at the front end thereof is a manually operable ball projector 20 carried in the front wall 16. The upper end of the board 18 is formed with an 20 arcuate track piece 21 to lead the projected balls to a cushion 22 from which the balls rebound to 25 gravitate down the board 18. Across the lower edge of the board 18 is a transverse partition 23 having inclined rear edges to cause a ball rolling thereto to be led to a central hole 24 to drop therethrough and be caught by a shallow transverse inclined trough 25 which leads such balls back into the passage 19 to gravitate back into 30 position to be rolled over again by the projector 20. This gives the player a free play of all balls missing the main holes arranged over the game board.

Forwardly of the lower end of the board 18 between the partition 23 and front wall 16 is a register plate 26 having two longitudinally spaced, transverse register slots 27, 28 formed therein as shown. As shown in Figures 6 and 7 a cross plate 29 is slidably mounted on supports or tracks 30 carried by the side walls of the cabinet beneath the register plate 26. This plate 29 is secured at 31 to a conventional form of coin 35 released slide 32 so that when the slide is moved the plate 29 and all structure connected therewith moves also. The plate 29 includes a downwardly and forwardly extending tray member 33 having in its horizontal portion a series of spaced ball drop holes 34.

Extending rearwardly and connected to the plate 29 are bars 35 carrying another cross plate 36 including a downwardly and rearwardly extending member 37 having in its horizontal leg or tray portion a series of spaced ball drop holes 38 formed therein. The member 37 is relatively higher than the corresponding member 33 as shown in Figure 6. Underneath these members 55 is a U-shaped ball collecting and segregating trough 39 (see also Figure 2), which trough portions are reversely inclined in a transverse direction. Thus balls falling through the holes 38 drop into the high or rear trough portion and gravitate to the left hand end thereof where the U routes them into the low front trough portion, which inclines toward a ball lifter to be described now and located in the right hand side wall of the cabinet.

65 The lifter comprises as shown in Figures 1 and 8 a vertical plunger 40 slidable up and down manually in a vertical bore 41 formed in a depended portion of the cabinet side wall. Said wall is slotted at 42 to allow for the travel of a 70 knob 43. When the plunger is down, one ball from the trough can gravitate onto the head of the lifter 40, whereupon the lifter can be moved upwardly by the knob 43 to raise the ball into the passage 19 in position to be hit by the projector 20.

The under side of the register panel 26 carries suitable guide strips 44 for a series of transversely spaced, longitudinally slideable, substantially horizontal registers 45 movable away from, or under, the register slot 28. These registers 45 are independently movable and each includes a depending angular leg 46 adapted to be engaged by balls rolling down a supplementary grooved alley board 47, said board 47 being located a sufficient distance below the rear trough portion of 10 the trough 39 to permit free rolling of the balls on said board 47. Each register 45 includes a stop pin 48 to limit the forward movement thereof so that the registers cannot run out from between their guides 44.

Similarly the plate 26 rearwardly of the other register slot 27 carries guide pieces 49 on its under side for similar slidably mounted rear, individual, registers 50 having each a stop 51 and depending legs 52 to be engaged by balls rolling 20 down short alleys 53 which are each longitudinally slotted at 54 to permit small balls to drop therethrough to the lower alley 47 to set the registers 45 while the larger balls cannot fall through and therefore roll down the alleys 53 to set the 25 registers 50.

Scattered over the board 18 and formed therethrough are a number of ball drop holes 55, each said hole being half rounded at their rear ends to receive the balls and formed with parallel 30 longitudinal side edge portions toward their forward ends by notching out the board as at 56. The holes are so shaped, each to receive a tubular and U-shaped depending ball guide 57 which as shown in Figures 4, 5 and 6 are each slotted 35 vertically at their front edge and spread apart to form parallel sides 58 to fit the notched hole 55. These sides 58 in each hole 55 include upstanding ears 59 to carry a pivot pin 60 for hingedly mounting a trap door 61 having wings 40 62 for normally resting the doors on the board 18 as shown in Figure 4 in hole opening position. The door is so held by its own weight.

Further each door includes a trip leg 63 extending angularly from the door 61 and normally in a position within the hole 55 to obstruct the same so that a ball entering the hole must engage the leg 63 to pivot the door 61 downwardly to hole closing position in an obvious manner. Each guide 57 is U-shaped at 58 as 50 shown in Figure 10, in cross section, and has its lower end cut off at an angle as at 64 to provide another U-shaped cross section as shown in Figure 9.

A ball dropping through any hole 55 closes the 55 trap door 61 and then drops down through the board 18 onto a guide or alley member made up preferably of a number of channel members which may be half round pipe-like sections 65 arranged in parallelism side by side and welded 60 together to form an alley panel stationarily mounted on the walls of the cabinet as shown in Figure 6. There is one such lengthwise groove or alley 65 under each hole 55 and the guides 57 are U-shaped properly to direct each falling ball 65 with certainty onto its alley 65, said guide members 57 being associated with the alley panel 65 between it and the top board 18. It is noted that each alley or groove 65 guides a ball onto the alley board 53 which has alined grooves or tracks as 70 heretofore described.

The slide bars 35 at their rear ends are connected by a cross bar 66 which carries a number of push rods 67 there being one over each groove 65 and one for engaging the leg 63 of each trap 75

door 61. These rods are of different lengths as the holes 55 are differently spaced lengthwise along the board 18. When the slide 32 is moved everything connected thereto is also moved, such 5 for example as the plate 29, bars 35, 66 and rods 67.

In Figure 11 we have shown a modified form of 10 register which here is pivotally mounted under the register plate 26 and its slot 27 at the discharge end of the ball trough or chute 53. The 15 side walls of the cabinet 15 carry a transverse pivot shaft 68 to which is pivotally connected intermediate their ends a series of independent 20 register segments 50' having legs 52' adapted to 25 be engaged by a rolling ball to set and hold the register. The pivotal movement of the leg 52' is limited by a transverse stop wire 69 so that the ball cannot drop through the holes 38 until the part 37 is shifted rearwardly. 30 The game board 18 on its top surface may be ornamented by card designations such as the diamond, spade, club, and heart, shown, and each hole 55 may be appropriately marked to show the various cards in each suit and the registers 50, 45, 50' may carry corresponding respective designations to make possible the playing of a simulated poker card game, as has been stated.

In starting the game play, as a poker hand drawing game, two players may play in turn, each 35 having five balls available for projection over the board. The five small balls always are projected by the first player as these balls, because of their manner of segregation in the U-trough 39 always are first in position adjacent the lifter 40 so naturally they are the first balls to be played. The balls are raised by the lifter 40, one at a time, from the lower end of the trough 39 into position in back of the projector 26 in the passage 19, which at its front end is preferably 40 depressed below the level of the board 18. When the small balls are so projected, they gravitate from the high end of the board 19 downhill, and possibly into the holes 55, wherein the trap doors, or checks 61 are in hole uncovering position. As 45 a ball drops through a hole 55 it presses down on the leg trip 63 of the door to pull the same downwardly to hole closing position so that only one ball, during a game cycle can drop through a given hole. Each hole will have some card designation such as king of clubs, queen of spades, etc., which marking may if desired be placed on each door check 61.

The ball dropping through the hole as described is definitely guided by the member 57, 55 which is U-shape in cross section, onto a guide alley 65 to permit the ball to roll down the same to the alley extensions 53. As has been stated these extensions comprise spaced tracks to leave slots 54 so that the small balls drop through and 60 onto the chute or lower alley guide 47 that directs each small ball to the leg 46 of the register 45 that corresponds with the designation on the door of the hole that trapped a ball. Accordingly the small ball being discussed lodges against 65 the leg 46 to slide the register 45 thereof into view under the register slot 28, the register stopping its sliding movement in the form of Figure 6, when it hits the rear edge of the plate 29. The leg 46 is now in such position with respect to the 70 ball drop hole 34 adjacent the same that the ball cannot drop through, as is shown in the dotted lines in Figure 6.

In the same fashion, all of the five small balls are played, trapped and registered, any spent balls 75 dropping into the hole 24 are returned into posi-

tion adjacent the projector for free replay by means of the shallow trough 25 in the manner previously described. With the first five balls played the first player has in effect now drawn a five card poker hand. All five small balls are now 5 accumulated on the tray or ball support 34 just over the front portion of the ball return trough 39.

The second player now operates the lifter 40 to elevate the five large balls into projecting 10 position for play. These balls are played in the same manner described, to be trapped by the holes 55, thereby closing the trap doors 61. The dropping balls are similarly guided by the respective guides onto the proper alley 65 and over the 15 extension 53 thereof. These large balls cannot fall through the slots 54 because of their size and consequently they engage and set the legs 52 and associated registers 50 under the slot 27, the balls remaining in the dotted line position shown in 20 Figure 6 on the tray 37 without falling through the holes 38. After each player has thus played his five balls the two five card hands drawn appear registered in the slots 27, 28 where they can 25 be compared to determine the winner.

All balls are now lodged on the portions of the tray members 33, 37 having the holes 34, 38 there-in above the front and rear runs of the reversely inclined trough 39. By coin releasing the slide, 30 the same may be pushed rearwardly into the cabinet to move the plate 29 and all connected parts described. Thus each tray member 33, 37 moves rearwardly to center the holes 34, 38 under the balls whereupon they are released to drop into the portions of the trough 39 thereunder. Obviously the small balls travel the shortest distance and reach the lifter 40 ahead of the large balls. Thus the U-shaped trough 39 functions to segregate the five large balls from the five small balls. 35

With the same movement of the plates 29, 36 40 the registers 45, 50 are pushed rearwardly away from under the respective slots 28, 27 to position the same in non-registering positions. At the same time the bar 66 moves the rods 67 to engage the depending legs 63 of the closed doors 61 to 45 push the same upwardly to their hole uncovering positions, each guide 57 being open at its front edge because of the spread ears 58 to accommodate these rods 67 as shown in Figure 4. With all parts now reset for play the slide 32 is 50 pulled out to return the shiftable parts described and connected thereto to their forward game playing position as will be understood.

The modified registers 50' of Figures 11 and 12 55 work in obviously the same ball actuated manner heretofore described, except that they pivot on the shaft 68 instead of slide as in the form of Figure 6. The stop wire 69 insures that the leg 52' thereof will not swing forwardly too far lest the ball drop through the holes 38, it not being desirable to drop the balls until the member 37 is shifted in the manner now understood. The weight of the leg 52' is so disposed with respect to the fulcrum 68 that the indicator segments 50' are 60 normally held in non-registering position.

It is the intention to cover all changes and variations of the example of a game structure herein selected for purposes of illustration which do not depart from the spirit and scope of our invention as hereinafter claimed. 70

What we claim is:

1. An amusement game having an inclined board over which balls may be rolled to drop through holes formed in the board, an inclined alley member below the board to receive and 75

- guide the balls received from the holes, a slotted register plate at the lower end of the board, movably mounted registers carried under the plate and having depending legs located in position, at the end of the alleys to be engaged by the balls rolling down the alleys to move the registers into view under the slot in the plate, and means included in the game to temporarily hold the balls in register setting position.
5. An amusement game having an inclined board over which balls may be rolled to drop through holes formed in the board, an inclined alley member below the board to receive and guide the balls received from the holes, a slotted register plate at the lower end of the board, pivotally arranged registers located on the under side of the plate and having pendant legs located adjacent the ends of the alleys to be engaged by the balls rolling down the alleys to rock the registers into view under the slot in the plate, and means included in the game to temporarily hold the balls in register setting position.
10. An amusement game having an inclined board over which balls may be rolled to drop through holes formed in the board, an inclined alley member below the board to receive and guide the balls received from the holes, a slotted register plate at the lower end of the board, pivotally arranged registers located on the under side of the plate and having pendant legs located adjacent the ends of the alleys to be engaged by the balls rolling down the alleys to rock the registers into view under the slot in the plate, and means included in the game to temporarily hold the balls in register setting position.
15. An amusement game having an inclined board over which balls may be rolled to drop through holes formed in the board, an inclined alley member below the board to receive and guide the balls received from the holes, a slotted register plate at the lower end of the board, pivotally arranged registers located on the under side of the plate and having pendant legs located adjacent the ends of the alleys to be engaged by the balls rolling down the alleys to rock the registers into view under the slot in the plate, and means included in the game to temporarily hold the balls in register setting position.
20. An amusement game having an inclined board over which balls may be rolled to drop through holes formed in the board, an inclined alley member below the board to receive and guide the balls received from the holes, a slotted register plate at the lower end of the board, pivotally arranged registers located on the under side of the plate and having pendant legs located adjacent the ends of the alleys to be engaged by the balls rolling down the alleys to rock the registers into view under the slot in the plate, and means included in the game to temporarily hold the balls in register setting position.
25. An amusement game having an inclined board over which balls may be rolled to drop through holes formed in the board, an inclined alley member below the board to receive and guide the balls received from the holes, a slotted register plate at the lower end of the board, pivotally arranged registers located on the under side of the plate and having pendant legs located adjacent the ends of the alleys to be engaged by the balls rolling down the alleys to rock the registers into view under the slot in the plate, and means included in the game to temporarily hold the balls in register setting position, a trough below said means, and means to reset the registers to non-indicating positions and release the balls to fall into said trough.
30. An amusement game having an inclined board over which balls may be rolled to drop through holes formed in the board, an inclined alley member below the board to receive and guide the balls received from the holes, a slotted register plate at the lower end of the board, pivotally arranged registers located on the under side of the plate and having pendant legs located adjacent the ends of the alleys to be engaged by the balls rolling down the alleys to rock the registers into view under the slot in the plate, and means to temporarily hold the balls in register setting positions, a trough below said means, and means to reset the registers to non-indicating positions and release the balls to fall into said trough.
35. An amusement game having an inclined board over which balls may be rolled to drop through holes formed in the board, an inclined alley member below the board to receive and guide the balls received from the holes, a slotted register plate at the lower end of the board, pivotally arranged registers located on the under side of the plate and having pendant legs located adjacent the ends of the alleys to be engaged by the balls to rock the registers into view under the slot in the plate, means to temporarily hold the balls in register setting positions, a trough below said means, and means to reset the registers to non-indicating positions and release the balls to fall into said trough.
40. An amusement game having an inclined board over which balls may be rolled to drop through holes formed in the board, an inclined alley member below the board to receive and guide the balls received from the holes, a slotted register plate at the lower end of the board, pivotally arranged registers located on the under side of the plate and having pendant legs located adjacent the ends of the alleys to be engaged by the balls to rock the registers into view under the slot in the plate, means to temporarily hold the balls in register setting positions, a trough below said means, and means to reset the registers to non-indicating positions and release the balls to fall into said trough.
45. An amusement game having an inclined board over which balls may be rolled to drop through holes formed in the board, an inclined alley member below the board to receive and guide the balls received from the holes, a slotted register plate at the lower end of the board, pivotally arranged registers located on the under side of the plate and having pendant legs located adjacent the ends of the alleys to be engaged by the balls to rock the registers into view under the slot in the plate, means to temporarily hold the balls in register setting positions, a trough below said means, and means to reset the registers to non-indicating positions and release the balls to fall into said trough.
50. An amusement game having an inclined board over which balls may be rolled to drop through holes formed in the board, an inclined alley member below the board to receive and guide the balls received from the holes, a slotted register plate at the lower end of the board, pivotally arranged registers located on the under side of the plate and having pendant legs located adjacent the ends of the alleys to be engaged by the balls to rock the registers into view under the slot in the plate, means to temporarily hold the balls in register setting positions, a trough below said means, and means to reset the registers to non-indicating positions and release the balls to fall into said trough.
55. An amusement game having an inclined board over which balls may be rolled to drop through holes formed in the board, an inclined alley member below the board to receive and guide the balls received from the holes, a slotted register plate at the lower end of the board, pivotally arranged registers located on the under side of the plate and having pendant legs located adjacent the ends of the alleys to be engaged by the balls to rock the registers into view under the slot in the plate, means to temporarily hold the balls in register setting positions, a trough below said means, and means to reset the registers to non-indicating positions and release the balls to fall into said trough.
- through holes formed in the board, an inclined alley member below the board to receive and guide the balls received from the holes, a slotted register plate at the lower end of the board, said plate presenting two spaced transverse slots, a bank of movably mounted registers under each slot, said registers including depending legs, means for routing balls from the alley member to engage the legs of the registers to set the same into registering positions, means to retain the balls lodged against said legs, a continuous U-shaped trough having reversely inclined transverse runs arranged below said ball retaining means, and means to reset the indicators and dislodge the retained balls to fall into said trough.
6. An amusement game having an inclined board over which balls of two sizes may be rolled to drop through holes formed in the board, an inclined alley member below the board to receive and guide the balls from the holes, a register plate at the lower end of the board having a pair of transverse longitudinally spaced slots formed therein, a bank of transverse movably mounted independent registers located under each slot, said registers including pendant legs, means for segregating the balls according to size and causing one size of balls to roll from the alley member to lodge against the legs of one set of registers to move the same into registering position under one slot and for causing the other size of balls to move the registers in the other set into registering positions relative to the other slot, means to retain the balls temporarily in their register setting positions, a pair of communicating troughs arranged below the retaining means, and means to reset the registers to non-registering position and release all balls to fall into said troughs.
7. A game provided with an inclined board having holes therethrough down which balls may gravitate to the holes, an inclined panel having passageways to trap balls dropping through the holes, a register for the balls rolling down the passageways comprising a slotted register plate located at the lower end of the passageways, a transverse shaft beneath said plate, register segments having legs pivotally connected to the shaft intermediately their ends, said legs being positioned to be engaged by the balls to move the segments into registering position under the slotted register plate.
